UNITED STATES PATENT OFFICE

ALFRED SCHWARZ, OF MONTCLAIR, NEW JERSEY

APPARATUS FOR DISTILLING OIL

Application filed June 16, 1928. Serial No. 285,855.

My invention relates to the distillation of hydrocarbon oils and more particularly has reference to a process and apparatus for cracking such oils whereby the annoyance due to separation of carbon from the oil during cracking is reduced to a minimum, and increased gasoline yields obtained.

In my co-pending application Serial No. 67,217, filed November 6, 1925, I have disclosed a process and apparatus for distilling oil according to which a heating element is suspended into the still from a detachable cover, the carbon separated from the oil during treatment being collected on the heating element which is removed for cleaning or replacement after a certain amount of carbon has accumulated thereon.

In the process and apparatus of my prior application above referred to, the removable heating element is suspended in a relatively large body of oil with the result that the heat is distributed throughout the oil body so that only a relatively small amount of cracking takes place due to the fact that only a small percentage of the total oil body in the still comes into direct contact with the heater. Consequently only a relatively small part of the entire oil body is heated to cracking temperature so that there is considerable utilization of heat for simple distillation instead of for cracking and the cracking operation is not wholly efficient with respect to the large body of oil initially placed in the still.

In the development of the process and apparatus of my prior application, I have found that the distillation and cracking are materially enhanced and larger yields of light hydrocarbons such as gasoline may be obtained if only a relatively small body of oil is heated at any one time. For example, in the ordinary oil still where several hundred barrels of oil are heated at the same time with a given heat in-put, the yield of gasoline range distillate is only about 1 to 2%. On the other hand, if only about three of four barrels of oil are heated at one time in contact with a relatively large heating element so arranged as to pass the oil parallel to the heating surfaces in a relatively

thin layer so as to keep it in contact with said heating surface as long as possible, the same heat in-put as employed in the preceding example will be applied to all portions of the oil within the still and a gasoline distillate yield of 15 to 30% may be obtained. This increased gasoline yield is due to increased cracking.

It is therefore an object of my present invention to provide an improvement upon the process and apparatus disclosed in my prior application Serial No. 67,217 whereby only a relatively small body of oil is heated at any one time by contact with an internal heater suspended in the oil and upon which the separated carbon is allowed to collect.

In my present process the cracking operation is made continuous by causing a relatively narrow stream of oil to flow continuously in contact with the heating element, and in the preferred embodiment of my invention, I prefer to maintain a constant oil level in the still, replenishing the oil removed in the form of vapor by raw charging stock in such amount as to maintain the oil level constant. The heater being removable, it may be periodically removed from the still when carbon deposition thereon has collected in proper thickness, the heater being cleaned and replaced or a fresh heater substituted therefor. I may employ a battery of stills all connected with a common fractionating tower so that one unit may be cut out of the system for cleaning while the others are maintained in operation.

In my present invention there is employed, as already stated, a removable heater suspended in the oil in a manner similar to that of my prior application referred to with the distinction, however, that the oil is caused to flow in a relatively thin stream into contact with the heater, the inner still wall and the outer surface of the heater forming the restraining surfaces between which the oil flows. For best results the distance between these surfaces should not be in excess of three inches so that a thin stream of oil no more than three inches in thickness is heated at any one time. In

this manner of heating it will be seen that the heat concentration is much higher per unit volume of oil than when a relatively large body of oil is being treated so that each particle of the oil in the still is rapidly raised to a cracking temperature and vaporized with the result that the oil within the still at any one time remains there for only a short interval so that it is possible to feed oil into and through the still quite rapidly. As the carbon separates from the oil during cracking, it deposits upon the heating surface which may be removed for cleaning at intervals. I prefer to permit the carbon to accumulate in a layer of approximately one-half to two inches in thickness before removal. It will be understood that when fresh charging stock is pumped into the still, very little carbon is separated for a considerable period of time, this being due to the fact that the oil is only partially distilled and only partial chemical inter-reactions take place between the molecules. After a certain duration of heating, however, the contents of the still reaches a critical point, most of the light stock having been removed and also most of the liquid phase reactions having taken place. The oil has approached the stage where destructive distillation occurs and cracking takes place very rapidly with more rapid deposition of carbon. Gas and vapor are set free and at this critical period the carbon deposition becomes so rapid that the operator must keep close watch on the carbon accumulation. For this purpose there is provided a small rod passing through a stuffing box on the outer shell of the still and extending externally of the still in such a manner that the operator may gauge the thickness of the carbon on the heating element.

For a more detailed understanding of the invention reference will be had to the accompanying drawings which show several embodiments of my invention, these being for illustrative purposes only, and are not to be construed as limiting the invention. In the drawings:

Fig. 1 is a vertical section through one form of my invention;

Fig. 2 is a vertical section through a modified form of apparatus;

Fig. 3 is a plan view of a battery of stills in accordance with my invention;

Fig. 4 is a view of a pair of stills forming part of the battery shown in Fig. 3 and illustrating various appurtenances; and

Fig. 5 is a view similar to Fig. 1 showing an improved oil gauge attached to the still.

Referring more particularly to the drawings, there is shown in Fig. 1 an outer cylindrical casing 10 forming the still proper and having the customary vapor outlet 11 and oil inlet 12, which inlet may also be employed for discharge of oil upon completion of a

run and prior to removal of the heater hereinafter described. At 13 is shown an additional valved outlet. The top of the casing 10 is provided with a peripheral flange 14 extending outwardly therefrom as shown. Resting upon the flange 14 is the peripheral flange 15 of a hollow cylindrical inner casing 16 having a closed bottom 17 and an open top as shown in Fig. 1. By reference to Fig. 1, it will be seen that the cylindrical casing 10 and the concentric cylindrical casing 16 form a closed annular passage 18 through which the oil may flow. A removable top or cover 19 having peripheral flange 20 rests upon the flange 15, the flanges 14, 15 and 20 being bolted together as shown at 21 for ready detachment of the top 19 and cylinder 16 from the casing 10 so that the member 16 may readily be removed from the still when desired. Attached to, in any suitable manner, or integral with the top plate 22 of the cover 19, is a hollow open-ended cylindrical member 23 of any suitable refractory material, preferably of carborundum, the member 23 terminating a short distance above the bottom 17 of the casing 16 as shown in the drawings. At 24 there is conventionally shown an oil burner having oil inlet 25 and air inlet 26, the burner extending through the top plate 22 and into the cylindrical member 23. Any other means may be substituted for the burner 24 for supplying a heating medium to the member 23. The burner may be replaced by a superheated steam inlet or an inlet for flue gases or other heating medium. The cover 19 is provided with flue or inlet 27 for discharge of the spent heating medium. The outer surfaces of the still and cover are preferably provided with a heat insulating layer (not shown).

In operation of the device illustrated in Fig. 1, the oil to be distilled or cracked is fed through the inlet 12 into the annular passage 18 up to the level indicated at 28. The burner 24 is set into operation and the hot gases discharged therefrom pass downwardly through the cylindrical member 23, and upwardly through the passage 29 formed by the member 23 and casing 16 and thence to the outlet 27. The flow of hot gases through the passage 29 heats the surface 16 to a distilling or cracking temperature, and this heat is rapidly imparted to all portions of the annular column of oil surrounding the same due to the fact that the column is relatively thin, being no more than three inches in thickness, as stated. As the oil is cracked and vaporized, fresh charging stock is fed in through inlet 12 in sufficient quantity to maintain the oil level 28 constant. Since all parts of the annular oil column quickly attain a cracking and vaporizing temperature, vaporization progresses rapidly with discharge of vapors through outlet 11 and oil

being fed in quite rapidly at the bottom of the still. Consequently any one particle of oil remains in the still but a short time so that a considerable volume of oil can be heated and cracked per unit of time. The temperatures are, of course, varied with the particular character of oil being treated and with the products desired, and for cracking a relatively heavy stock into gasoline hydrocarbons, the preferred temperature will vary between 750° F. to 1000° F. Of course, higher temperatures may be employed depending upon the character of the charging stock and products desired. Any desired superatmospheric pressure may be employed and this too will vary with other factors in the operation such as character of oil treated, products desired, temperature, etc. However, I find that superatmospheric pressures are unnecessary in ordinary practice due to the fact that the cracking heat of the surface 16 is rapidly imparted to the thin column of oil in contact therewith so that heavy pressures are not required to maintain the oil particles in contact with the heating surface for a prolonged period as in the cracking processes now in use. Where cracking is not desired as in straight run distillation, the still may be maintained under vacuum to quickly remove the evolved vapors from the source of heat.

During cracking carbon will accumulate upon the surface 16 and eventually tend to clog up the apparatus. By virtue of the fact that the hollow heater 16 is made removable such clogging up is prevented, and I prefer to remove the heater for cleaning or replacement after it has received a carbon layer of about one-half to two inches in thickness. Since the area of the heating surface 16 is relatively large as compared to the thickness of the annular oil column surrounding the same, a two inch layer of carbon on the surface 16 represents a considerable mass as compared to the volume of oil treated at any one time, and consequently the still may be operated for a considerable time before it becomes necessary to remove the heater. In order to remove the heating surface 16 and its accumulated deposit of carbon, it is simply necessary to loosen the bolts 21, remove the cover 19, and then hoist the heater out of the still. Before removing the heater it is preferable that the still be dry and for this purpose the oil within the still may be pumped back through pipe 12 and mixed with the feed stock for reintroduction into the still after cleaning or the oil may be separately discharged through outlet 13. It is often desirable to wash out the still before removal of the heater and for this purpose the oil may be surged back and forth to and from the source of supply once or twice through pipe 12. Although the cylindrical member 16 of the heating ele-

ment is shown as separate from the cover 19, it may be made integral with the latter as shown in my prior application referred to so that the entire heater may be removed with the cover.

In Fig. 2, I have shown a modified form of apparatus constructed so that the number of internal removable heaters may be increased or diminished at will in order to vary the amount of oil treated per unit of time. By virtue of this modified construction, if it becomes necessary to treat a large volume of oil in a short period of time, it is simply necessary to increase the size of the still and the number of heaters, although by such enlargement of the apparatus the relatively thin column of oil is not enlarged.

Referring to Fig. 2, I have shown a casing 10' which is made up of sections 10^a, 10^b, 10^c, and 10^d, these sections being flanged and bolted together as shown at 10°. The section 10^a is provided with liquid inlet 12' which may also be employed as a liquid discharge prior to removal of the heaters as explained in connection with the construction of Fig. 1. The section 10^a is provided with an additional valved liquid outlet 13' and vapor outlet 11' at a high point in the casing. By the construction so far described, it will be seen that the casing 10' may be expanded to hold a larger volume of oil by merely introducing one or more additional sections similar to 10^b and 10^c, or the casing 10' may be diminished in size by removal of the sections 10^b and 10^c and bolting together the flanges of the sections 10^a and 10^d.

In Fig. 2, I have shown the casing 10' equipped with two internal heating flues 16', but it will be readily seen that any number of such flues may be employed as explained above. The heating flues are adapted to receive any suitable heating medium such as combustion gases, superheated steam, hot air, mercury vapor, etc., the particular heating medium forming no part of the present invention. The flues 16' extend horizontally through the still or casing 10' and are removably supported in the ends (not shown) of the still or casing. Each of the flues 16' is made up of similar sections 16^a and 16^b, which sections are provided with longitudinally extending flanges 16^a and 16^b respectively, and the flanges adapted to be bolted together at points along the length thereof as shown at 16°. By this construction each flue may be separated into sections to facilitate the removal and cleaning thereof. It will be seen that by the construction illustrated in Fig. 2, in order to remove the flues for cleaning or replacement, it is merely necessary to separate either the still section 10^a or 10^d from the other still sections and remove the flues either as an entirety or as 130

separate sections 16^a and 16^b by unbolting the flanges at 16^c.

The operation of the device shown in Fig. 2 is similar to that of Fig. 1, the oil being charged into the still through pipe 12' up to the level 28', and this level being maintained constant by continuous introduction of fresh charging stock. The other steps of procedure are similar to those described in connection with Fig. 1, the oil being passed through the still as a column no more than three inches in thickness and the carbon collected upon the heaters which are removed and cleaned or replaced after they have received a carbon deposit of one-half to two inches in thickness. In this operation, however, a considerably larger volume of oil may be distilled or cracked per unit of time without altering the thickness of the column of oil in the still and the still may be expanded or contracted in size to meet the particular demands of the oil refiner.

In Figs. 3 and 4, I have more or less diagrammatically illustrated a battery of stills arranged so that one or more units thereof may be cut out of the system for cleaning while the others are in operation. As will be seen from Figs. 3 and 4, the stills 10 are arranged in two parallel rows, all the stills discharging vapors through valved outlets 50, manifolds 51, and vapor lines 52 to a common dephlegmator or reflux condenser 53. The construction of each still in the battery is similar to that shown in Fig. 1 or they may be constructed as shown in my copending application Ser. No. 67,217, the main points being that the internal heaters are easily removable and that the oil is treated in a relatively thin column which surrounds the heater. Charging stock is fed to the different still units of the battery through valved inlets 54 from the manifolds 55 connected to feed pump 56 by line 57 and liquid oil may be discharged from the stills prior to cleaning through the inlet means or through the auxiliary outlets 58. Uncondensed vapors in the reflux condenser 53 issue therefrom through vapor outlet 59 to a condenser conventionally shown at 60, the condensate and gases passing by pipe 61 to distillate receiver 62 from which the fixed gases issue by pipe 63 to a gasometer 64. If cracking is being performed in the stills 10, the reflux condensate formed in the dephlegmator 53 is returned therefrom to any one or more of the stills by return line 65 and valved pipes 66 to the reflux manifolds 67 and valved pipes 68 to any chosen still or stills. Any desired superatmospheric pressure may, of course, be employed, which pressure may be varied. If only fractional distillation and not cracking is desired, superatmospheric pressure will not be employed but instead the stills may be vac-

uumized and reflux condensate will not be returned to the stills but may be withdrawn from the system. The operation in each of the stills 10 of the battery is similar to that described in connection with Figs. 1 and 2, but by means of the system just described, the shutting down of the entire system is not necessary as one or more of the stills may be alternately cut out of the system for cleaning while the others are kept in operation.

In Fig. 5 I have shown a still construction similar to that of Fig. 1 provided, however, with an improved form of liquid level gauge for ascertaining at any time the liquid level in the still. The usual type of glass gauge applied to stills containing heavy oils has the defect that the heavy oil clouds or fogs the gauge glass with the result that the true liquid level cannot readily be determined. The gauge illustrated in Fig. 5 avoids this defect and is based upon the use in the gauge glass of a light liquid, preferably the light hydrocarbon oils obtained in cracking.

Referring to Fig. 5, I have shown at 70 a stand-pipe extending partially along the length of the still 10 and connected to the still by valved pipes 71 and 72 at a low point and a high point respectively. The stand-pipe 70 has a valved drain 73 at its lower end and has open communication with a small condenser 74 at its upper end through pipe 75. The condenser 74 is connected to vapor outlet 11 by valved pipe 76. A gauge glass 77 has communication at its upper and lower ends with the standpipe 70 through the valved lines 78 and 79 respectively. The glass gauge 77 is provided with a valved drain 80 at its lower end and a valved liquid inlet 81 at its upper end.

In use, the valved lines 71 and 72 being closed and the still charged with heavy oil to be cracked, the valved lines 78 and 79 are opened and the gauge 77 and stand pipe 70 filled with a light oil through the inlet 81. The valved lines 71, 72 and 76 are now opened whereupon the light oil level in the gauge glass and stand pipe assumes the liquid level in the still. As distillation in the still proceeds, light oil flows from the gauge and stand pipe into the still where it is vaporized. The valved line 76 being partially open and properly adjusted, a small part of the light vapors issuing from the still through outlet 11 is tapped from the latter and led into the condenser 74 and the condensate therefrom issues back into the stand pipe and gauge. In this way it will be seen that there is always maintained in the gauge glass 77 a freely flowing light oil rather than a heavy viscous oil which clings to glass surfaces. The light oil does not fog or unduly color the gauge glass with the result that the liquid level in the still is at all times ascer-

tainable. Were the gauge glass filled with the same liquid as contained in the still and undergoing cracking, the reading of the liquid level would be difficult, if not impossible. It will, of course, be understood that if fractional condensers or dephlegmators are employed in the system, the condenser 74 may be connected into the vapor line behind such fractional condensers or dephlegmators or even behind the final condenser if the light oil employed is more volatile than the final product of the process.

By virtue of the process and apparatus hereinbefore described, I am able to obtain high percentage yields of gasoline hydrocarbons with efficient utilization of heat input and comparatively little annoyance from carbon deposition as compared to prior methods and apparatus for cracking. The construction is relatively simple and permits of ready disassembly so that when shutting down a particular still for cleaning becomes necessary only a short period of time is lost in the operation. By virtue of the expandable and contractable construction shown in Fig. 2, it is possible to easily vary the size of the still from time to time in accordance with whether the refiner has on hand a large or small quantity of oil which must be distilled or cracked within a given period of time.

Although I have illustrated and described different modifications of my invention, it is to be understood that these are not limiting upon the invention as various changes and modifications may be made without departing from the spirit of the invention as expressed in the appended claims.

Having described my invention, what I claim and desire to secure by Letters Patent is:

1. An apparatus for cracking oils comprising an outer vertical casing provided with an oil inlet at the bottom and a vapor outlet adjacent the top and having an outwardly extending flange at its top portion, an inner casing concentric with said outer casing and having an outwardly extending flange removably supported on the flange of said outer casing, the inner and outer casings forming a narrow closed oil passage, a cover for both said casings removably supported on the flange of said inner casing, means in said cover for supplying a heating medium to said inner casing, and an outlet in said cover for discharging spent heating medium from said inner casing.

2. An apparatus for cracking oil comprising an outer vertical casing provided with an oil inlet and a vapor outlet and having an outwardly directed flange at its top, an inner casing concentric with said outer casing having a closed bottom and an open top, an outwardly directed flange at the upper portion of said inner casing removably supported on

the flange of said outer casing, the inner and outer casings forming a closed narrow oil passage, a removable cover supported on the flange of said inner casing, an open-ended tube extending from said cover into said inner casing to a point above the bottom thereof, means for supplying a heating medium to said tube, and an outlet for said inner casing for removing spent heating medium therefrom.

3. The combination with an oil still having a vapor outlet of a standpipe having communication with the still at points above and below the liquid level in the still, a gauge glass communicating with said standpipe, a condenser, and means effecting communication between said vapor line and condenser and between said condenser and standpipe.

In testimony whereof I affix my signature.

ALFRED SCHWARZ.
